EYEGLASS FRAME OR SIMILAR ARTICLE

Alexander Kono, Woodside, N.Y., assignor to Kono Manufacturing Co., Inc., New York, N.Y., a corporation of New York

Filed Sept. 9, 1966, Ser. No. 3,788

Term of patent 14 years

(Cl. D57—1)

FIG. 1 is a perspective view of an eyeglass frame or similar article showing my new design;

FIG. 2 is a front view thereof;

FIG. 3 is a top view thereof;

FIG. 4 is a sectional view taken along line 4—4 of FIG. 2; and

FIG. 5 is an enlarged detail view of the surface ornamentation taken from the left of FIG. 2.

The dominant features of my design reside in the portions shown in full lines.

I claim:

The ornamental design for an eyeglass frame or similar article, substantially as shown and described.
